UNITED STATES PATENT OFFICE.

CHRIS KNUTSEN, OF PORT TOWNSEND, WASHINGTON.

DESIGN FOR A HARP-GUITAR FRAME.

SPECIFICATION forming part of Design No. 28,300, dated February 15, 1898.

Application filed May 17, 1897. Serial No. 636,996. Term of patent 14 years.

To all whom it may concern:

Be it known that I, CHRIS KNUTSEN, a citizen of the United States of America, residing at Port Townsend, in the county of Jefferson 5 and State of Washington, have invented a certain new Design for a Harp-Guitar Frame, of which the following is a specification, reference being had therein to the accompanying drawing.

10 My invention relates to a design for a harp-guitar frame. It relates to the entire configuration of the frame, and especially to the design for a harp-guitar frame as illustrated in the accompanying drawing, in which the 15 figure is a perspective view of the harp-guitar frame embodying my design.

The leading features of my design appear in the following description.

10 The body approximates in shape the usual 20 guitar form, from which the longitudinal fret-arm and finger-board extends and which terminates in the approximately V-shaped keyboard. On the left of the upper end of

the body a harp-shaped arm extends longitudinally, its converging sides tapering gradually outward from the fret-arm, thence somewhat abruptly inward where it joins the keyboard, and the side of the arm contiguous to the keyboard is formed with an auxiliary keyboard or peg-head, as shown. On the 30 body of the guitar-frame there appears two hearts, with their apices turned outward, and centrally below them is a five-pointed star. On the arm a crescent bisected by a diamond is seen.

Having thus fully described my design, 35 what I claim is--

The design for a harp-guitar frame, substantially as herein shown and described.

In testimony whereof I hereunto affix my 40 signature in presence of two witnesses.

CHRIS KNUTSEN.
